CHAIR

Morris F. Fisher, Carmel, Ind., assignor to Mohasco Industries, Inc., Amsterdam, N.Y.

Filed Jan. 6, 1971, Ser. No. 104,535

Term of patent 14 years

Int. Cl. D6—02

U.S. Cl. D6—39

The figure is a perspective view of a chair embodying my new design. The side not shown is like the side shown except for the omission of the handle while the back of the chair is conventionally plain and unornamented.

I claim:

The ornamental design for a chair, substantially as shown and described.
